EX

OR D 16,134

DESIGN.

—o—
L. K. FULLER.

ORGAN CASE.

No. 16,134.

Patented June 23, 1885.

UNITED STATES PATENT OFFICE.

LEVI K. FULLER, OF BRATTLEBOROUGH, VERMONT.

DESIGN FOR AN ORGAN-CASE.

SPECIFICATION forming part of Design No. 16,134, dated June 23, 1885.

Application filed April 27, 1885. Term of patent 14 years.

To all whom it may concern:

Be it known that I, LEVI K. FULLER, a citizen of the United States, and a resident of Brattleborough, in the county of Windham and State of Vermont, have invented or produced a new and original Design for Organ-Cases, of which the following is a specification.

My design is clearly shown in the accompanying photographic illustration, in which A designates the front board of the case, B the key-board projection above the front board, C a strip above the key-board, D the back board of the case, and E the ends.

The general configuration of the case resembles that of ordinary cabinet-organ cases; but it differs from these in the particulars I will now set forth.

The front board, A, shows three panels, *a a a*, which are ornamented by linear patterns. The side panels are ornamented alike, and each has at the lower part an ornament comprising four horizontal lines, with a row of dots between the middle lines. Above this is an ornament comprising a horizontal band, on which are ornaments having the configuration of oblique squares. Above this latter band is an ornament of several horizontal lines, as shown. The central panel is ornamented in the same way as the side panels, except that the lower ornament of lines and dots is omitted. The corresponding ornamental bands and lines on the three panels *a a a* are in the same horizontal planes, as will be seen in the photograph.

The front of the key-board projection B is provided, as usual, with an open-work strip. This strip has two like ornaments, *b b*, each of which shows a pair of like ornaments, thus making four like ornamental designs in the strip. Each of these four designs simulates two straps or ribbons having each a diamond-shaped loop, with the ends of the straps crossing at an angle, as clearly shown in the photograph.

The strip C above the key-board is also an open-work strip of three parts, the two side parts, *c c*, being alike, and the central part, *d*, being higher and wider than the side parts, *c c*. Each of the side parts, *c*, is provided with an ornament in all respects similar to the ornament *b* in the strip B—that is

to say, it has a design simulating two straps having each a diamond shaped loop, with the free ends of the straps crossing each other at an angle.

The central part, *d*, has the following ornamentation: The top is horizontal and scalloped; in the center is a fan-like ornament representing rays and a semicircular band; the terminal rays of the fan ornament extend out to the sides near the top, and are curved at their ends, and below these on each side is a branched scroll ornament, which is clearly shown in the photograph.

The back board, D, rises high above the tops of the ends of the case, and this elevated portion is ornamented to simulate a hood-like projection or canopy extending from end to end of the case. The back board has three panels, *e g g*. The side panels, *g g*, are ornamented alike, and each has two horizontal linear ornaments, one above and the other below a central square ornament, on which is a lesser square ornament shown obliquely or diagonally to the first, all as clearly shown in the photograph. The central panel, *e*, is ornamented in the same way as the side panels, except that the central ornament is an oblong rectangle, on which are two oblique squares. The hood-like projection *h* of the back board has a front ornamentation of four bracket-like projections opposite to the division-lines between the panels *e g g*, and at the ends of the case four banister-like ornaments under said bracket-like ornaments, three strips between said bracket-like ornaments, on which are quarterfoil ornaments, a cornice-like ornament above this strip, and a frontispiece, *i*, ornamented as shown, above said cornice-like ornament.

Below the key-board projection, at its ends, are banister-like ornaments, *j j*, each of which has a square ornament at its center, and between this square and the front of the organ is a horizontal ornament which simulates a tie-piece.

On the projecting ends of the key-board projection B are bracket-like projecting ornaments *l l*.

On the end of the case are three projecting bracket-like ornaments, *m m*, with ornaments of a linear pattern on their sides; and these

ornaments *m* are further ornamented by a bar-like ornament, *n*, as clearly shown in the accompanying photograph.

It will be observed that the unity of the design as to its elemental features is preserved by giving to the most prominent ornamental band on the front board a diamond shaped or oblique square ornament very similar to that on the back board, and by making the designs to on the end panels of strip C similar to those on the strip of the key-board projection.

Having thus described my design, I claim as its novel features—

1. In an organ-case, the design which consists of a front board, A, showing three panels, *a a a*, the middle panel ornamented with a lower horizontal band, on which are oblique squares, and an upper ornament of several parallel horizontal lines, and the side panels having a like ornamentation to the central panel, and each having, in addition thereto, a lower ornament of four horizontal parallel lines and a row of dots, substantially as shown in the accompanying photograph.
2. In an organ-case, the design which consists of an open-work strip in the front of the key-board projection B, the ornamentation of said strip showing four like ornaments, each consisting of a design simulating two straps showing a diamond-shaped loop, and having their ends crossed, substantially as shown in the accompanying photograph.

3. In an organ-case, the design which consists of the ornamentation of the open-work strip C, which is the ornamentation on the central part, *d*, and the ornamentation on the two like side parts, *e e*, substantially as shown in the accompanying photograph.

4. In an organ-case, the design which consists of the ornamentation of the three panels *c g g* of the elevated back board, D, substantially as shown in the accompanying photograph.

5. In an organ-case, the design which consists of the ornamentation of the hood-like projection *h* of the back board, D, substantially as shown in the accompanying photograph.

6. In an organ-case, the design which consists of the ornamentation on the end of the case, said ornamentation comprising the three bracket-like ornaments *m* and the bar-like ornament *n*, substantially as shown in the accompanying photograph.

In witness whereof I have hereunto signed my name in the presence of two subscribing witnesses.

LEVI K. FULLER.
